Application August 6, 1946, Serial No. 688,782

11 Claims. (Cl. 249—60)

1

This invention relates to apparatus for refilling dispensing units for use in connection with the distribution or dispersion of insecticides, fumigants, hormones and the like.

The patent to Goodhue et al., No. 2,321,023, discloses a method of producing insecticidal aerosol which involves confining in a receptacle under super-atmospheric pressure a liquid gas containing in solution a suitable insecticide and releasing the receptacle contents, as desired, through a discharge orifice into the atmosphere. The receptacle contents are forced into the atmosphere by the high vapor pressure of the liquid gas, and the liquid solvent instantly evaporates into the atmosphere, separating the solute into particles of colloidal dimensions and leaving them suspended in the air, in the form of an aerocolloid, which is known as an aerosol. The receptacles generally are fitted with a discharge nozzle provided with a removable cap which, when screwed tightly onto the discharge nipple of the receptacle serves to open an internal valve and to release the contents of the receptacle in the form of a spray through a discharge orifice in the cap. When the cap is removed, the internal valve closes automatically to prevent loss of the receptacle's contents. Since these receptacles are comparatively expensive and refillable, they may be sent back to the manufacturer for refilling purposes. However, this is time-consuming and fairly costly.

An object of the present invention is to provide a field filling unit for distribution at convenient points or localities to which the users may bring such receptacles for refilling, thereby obviating the necessity of returning these receptacles to the manufacturer for such purposes.

Another and principal object of the invention is to provide a refilling apparatus in which no electrical connections or devices are necessary.

A further important object of the invention is to provide an apparatus that will refill such receptacles to a uniform over-all weight, including the weight of the receptacle and the filler.

Another object of the invention is to provide novel means for pumping and forcing the liquid filler from the supply tank to the receptacle being filled.

Other objects and advantages will appear hereinafter.

To the accomplishment of the foregoing and such other objects as may hereinafter appear, this invention consists in the novel construction and arrangement of parts hereinafter to be described and then sought to be defined in the

2

appended claims, reference being had to the accompanying drawing forming a part hereof which shows, merely for the purpose of illustrative disclosure, a preferred embodiment of the invention, it being expressly understood, however, that changes may be made in practice within the scope of the claims without digressing from the inventive idea.

In the drawing, in which similar reference characters denote corresponding parts—

Fig. 1 is a plan view of the apparatus of this invention;

Fig. 1a is a sectional, elevational view on a reduced scale of the supply tank;

Fig. 2 is a side elevation partially in section of the device of Fig. 1;

Fig. 3 is a fragmentary section taken along the line 3—3 of Fig. 2 and viewed in the direction of the arrows;

Fig. 4 is a fragmentary sectional view of a detail taken along line 4—4 of Fig. 1;

Fig. 5 is a similar enlarged fractional sectional view of another detail taken along line 5—5 of Fig. 1; and

Fig. 6 is an enlarged vertical section taken along the line 6—6 of Fig. 2 illustrating details of the mechanism for connecting the receptacle to be filled with the filling apparatus.

Referring now more specifically to Figs. 2 and 6, 10 is a generally cylindrical metal receptacle with dome-like ends, which is designed to receive under pressure a liquefied gas containing in solution an insecticide, fumigant, hormone or the like. This receptacle 10 may be approximately 6" long and approximately 3" in diameter, so that it may be readily held in a person's hand and directed as desired. At one end, the casing is provided with suitable means for discharging the receptacle contents into the atmosphere. This discharge means includes a tubular member 11 (Fig. 6) projecting through an aperture in one end of the receptacle 10 and preferably formed with a shoulder 12 which engages the outer surface of the receptacle end. A gas-tight seal is established between the receptacle 10 and the member 11 by any suitable means.

The inner end of the tubular member 11 is formed with a reduced diameter portion 13 around which tightly fits one end of a tube 13a extending substantially to the opposite end of the receptacle. The passageway through the member 11 is composed of three sections 14, 15 and 16 of progressively increasing diameter from the inner end of the member outwardly. In the 55 passageway 16 is provided an elastic ring 17,

preferably composed of synthetic rubber, such, for example, as neoprene, said ring being held in gas-tight sealing relationship and in place by an inwardly projecting lip 18. The member 11 is threaded exteriorly at 19 to form a nipple to receive a removable cap (not shown) having a discharge orifice through which the contents of the receptacle are discharged under pressure.

In the passageway 15, there is provided a helical expansion spring 20, one end of which supports a cup-shaped element 21 facing the ring 17. The cup-shaped element 21 has a bottom cylindrical recess 21a in which a valve operating rod, presently to be described, engages. The rim 21b of the cup-shaped element 21 is normally biased into sealing engagement with the ring 17 by the spring 20 so that its cup-shaped element, together with the ring 17, serves as a one-way valve normally sealing the contents of the receptacle therein. The removable cap (not shown) which screws onto the threaded portion 19 contains parts that operate to raise the cap rim 21 from its seat on the ring 17 to release the contents of the receptacle when desired. These parts are removed, together with the cap, when it is desired to refill the receptacle 10 and, therefore, are not shown. The receptacle 10, with its cap removed, is adapted when empty to be applied to the field filling apparatus now to be described for refilling.

Referring now more particularly to Figs. 1, 2 and 6, this filling apparatus comprises a guide shell 25 which is admeasured in dimensions to receive the receptacle 10 and to assist in supporting it vertically during the filling operation. This guide shell 25 has a drain cutlet 25a and an opening in its bottom in which a tubular member 26 is permanently fixed as at 27. This tubular member 26 has a passageway 28 which is internally threaded at 29 and admeasured in diameter and depth to receive the threaded portion 19 of the tubular member 11. The member 26 also has a passageway section 30 of larger diameter than the section 28 and these two sections are joined by a passageway section 31 of comparatively smaller diameter than either of the sections 28 or 30.

The tubular member 26 has an exteriorly threaded portion 32 and an unthreaded portion 33 of smaller diameter than the threaded portion 32 defining a shoulder 34. A tubular member 35, admeasured in diameter and in length to fit fairly loosely and slidably within the passageway 30, is provided. This tubular member 35 has a pointed lower end 35a and an annular flange 36. A latch expansion spring 37 is carried about the portion 33 of the tubular member 26 between the annular shoulder 34 and the upper surface of the flange 36 and functions as will be presently described. The tubular member 35 is held in place by a tubular member 38 which is internally threaded at 33a for threaded engagement with the threaded portion 32 of the tubular member 26. An annular shoulder 39 at the opposite end of the member 38 cooperates with the annular flange 36 to limit outward movement of the tubular member 35 relative to the passageway 30 induced by spring 37. The tubular member 35 has passageways 40, 41, 42 and 43 of progressively increasing diameter. An internally threaded passageway 44, in which a threaded nipple 45 having an internal passageway 46 may be screwed, provides access to the passageways 40, 41, 42 and 43 for purposes presently to be described.

As shown in Fig. 6, a helical biasing spring 47 is supported in the passageway section 41. An elastic ring 48 of rubber, such as neoprene or the like, and having a substantially T-shaped section, is supported in the passageway sections 42 and 43 above the helical spring 47. This ring is secured in sealing relationship upon the shoulder 49 by a washer 50 and ring nut 51 which is threadedly engaged in the threaded portion 52 of the passageway section 43.

A cup-shaped element 53, facing the ring 48, is supported on the helical spring 47. This cup-shaped element 53 has a bottom cylindrical recess 53a which is adapted to support one end of an upwardly projecting rod 54. The rod 54 projects upwardly of the cup-shaped element through ring 48, washer 50, ring nut 51, passageway 31 and into the passageway 28. This rod 54 has a central passageway 55, communicating passageways 56 at its lower end, as well as communicating passageways 57 near its upper end. The upper end of the rod 54 is reduced in diameter and admeasured to fit loosely within the reduced portion 21a of the cup 21 when the nipple portion 19 of the receptacle 10 is screwed into the threaded portion 29 of the tubular member 26. The lower end of the rod 55 fits fairly loosely within the reduced portion 53a of the cup-shaped element 53 to permit the rim 53b of the cup-shaped element 53 to accommodate itself to the lower surface of the neoprene ring 48.

The cup-shaped element 25, and the assembled parts just described, are supported suitably as shown in Figs. 1 and 2 by the arms 60 and 61 of a forked balance lever 62. These arms 60 and 61 are supported on a shaft 63 and the latter, in turn, is carried between the ball bearing supports 64, 65, provided in the oppositely located up-standing brackets 66, 67, these brackets being suitably supported from a table member 68. The portions 60a, 61a of the arms 60, 61 extend beyond the ball-bearing supported shaft 63.

A counterweight 69 is adjustably carried on these arm portions 60a, 61a for purposes presently to be described. The portions 60b, 61b of the arms 60, 61 extend forwardly of the tubular member 26, being bent closer to each other there, and are joined by a cross rod 70. The arms 60, 61 constitute a balance lever 62 whose fulcrum is the ball-bearing supported axle 63.

A yoke member 71 supported fixedly at 72 from the arms 60, 61 in turn pivotally supports at 73 a forked lever 74, this lever 74 in turn at 75 pivotally supporting a latch member 76. This latch member 76 is substantially L-shaped and one of its legs has a pawl member 77 at its end which extends between the arm portions 60b, 61b, and is engageable with the cross rod 70. A forked member 78 bearing a cross rod 79 between its tines is supported fixedly from the base 68 and is positioned to underlie the end 76a of the L-shaped latch member 76. The height of the cross rod 79 is so admeasured that when the balance arm 62 consisting of the levers 60, 61 is tilted in the clockwise direction of Fig. 2, to a predetermined extent, the latch or pawl member 77 will become disengaged from the cross rod 70. The lever 74 has a portion adapted to underlie the pointed end 35a of the tubular member 35 so that if the lever 74 is rotated in the counterclockwise direction of Fig. 2, sufficiently for the pawl 77 to engage the cross rod 70, the member 35 will be moved upwardly within the passageway 28 of the tubular member 26 against the action of latch spring 37 to substantially the position shown in

Fig. 6. As a result of this uplift, the rod 54 will be raised to the limit permitted by its annular flange 58 so that both the cup member 21 and the cup member 53 will have their respective rims 21b and 53b moved out of sealing engagement with respective rubber rings 17 and 48. On the other hand, when the balanced lever 62 tilts in the clockwise direction sufficiently for the end 76a to engage the cross rod 79, it will disengage the pawl 77 from the cross rod 70. The latch spring 37 will then move member 35 outwardly to the limit permitted by flange 39, and rotate the lever 74 in clockwise direction. The helical springs 20 and 47 will then be free and, through their biasing action, will restore the cup members 21 and 53 to their normally closed positions. The latter described position is the normal position of the parts within the tubular member 26.

The nipple 45 which extends laterally of the tubular member 35 near its lower end is joined by a suitable coupling nut 80 to an extension 81 of a tubular helical coil 82. The other end of this coil 82 is secured suitably to a coupling 83 carried fixedly, for example, by one of the brackets 66. A conduit 84 connects the coupling 83 with a conventional filter 85 (Fig. 1). This filter 85, in turn, is connected by conduits 86, 87 and 88 to the outlet nozzle 89, fitted with a one-way valve (not shown), opening outwardly, of a conventional hand pump 90. The inlet nozzle 91 of this pump 90, fitted with a one-way valve (not shown), opening inwardly, is connected by a conduit 92 to the outlet 93 of a supply tank 94 which contains the filling compound. A tubular extension or standpipe 93a extends from outlet 93 inwardly of tank 94 nearly to its bottom i. e. within $\frac{1}{4}$ " to $\frac{1}{8}$ ". The standpipe 93a is, of course, connected in leak-proof manner to the outlet 93. The reciprocating piston 95 of the hand pump 90 is connected pivotally at 96 to a yoke 97 which, in turn, is pivotally supported at 98 and operated by a removable lever arm 99. When out of operation, the lever arm 99 may be removed from the socket of the yoke 97 and carried in the spring brackets 100 fixed to the table member 68.

Operation of the device is as follows: Assuming that the filling tank has been suitably connected to the conduit 92 and that the operating lever 99 has been inserted into the socket of the yoke 97, the removable cap of the receptacle 10 to be filled is removed from the nipple of that unit. The receptacle 10 is inverted and its threaded portion 19 is screwed into the receiving thread 29 of the member 26. The lever member 74 is then rotated counterclockwise about its fulcrum 73 until the pawl 77 engages the cross arm 70, to maintain the said position of said lever 74. This serves to raise member 35 in opposition to latch spring 37 and to move the cup members 21 and 53 away from their seats on the rubber rings 17 and 48. Operation of the pump in one direction by lever 99 draws the filling fluid from the tank 94 through the one-way valve in nozzle 91 into the pump chamber. Then operation of the lever 99, in opposite direction, forces this fluid in the pump cylinder through the one-way valve in nozzle 89 and the conduits 88, 87 and 86, through the filter 85, and then through the conduit 84 and through the coiled tube 82 and its extension 81, through the passageways 46, 40, 41, 42, around the rim of cup 53, through the passageways 56, 55, 57, around the rim 21b of the cup 21 and through passageways 15 and 14 to the interior of the receptacle 10. As long as the pump is operated, fluid is transferred from the

tank 94 to the receptacle 10, as just described. The counterweight 69 is of such size that when the receptacle 10 is filled to a predetermined weight, the balance beam 62 is in equilibrium. 5 The center of gravity at this time of the whole moving system is above the center of rotation 63. As soon as the combined weight of the unit 10 and its filling is slightly heavier than the counterweight 69 or other counterbalancing means, such as a spring, it starts to rotate the balance beam 62 in clockwise direction, forcing the portion 60b, 61b of this beam downwardly. As soon as the beam 62 is rotated through any appropriate angle, there is an increasing torque tending to rotate it further in the same direction. When this beam 62 is rotated far enough to produce a substantial turning moment, the extension 76a of the latching arm 76 strikes the fixed stop 79, causing the ratchet arm 76 to rotate about its 15 fulcrum 75 and release the pawl 77 from the cross rod 70. The latching spring 37 is then free to move a tubular member 35 outwardly until the flange 36 strikes the shoulder 39, at which time the biasing springs 47 and 20 operate respectively to move the cup members 53 and 21 into sealing engagement with their respective rubber rings 17 and 48. The filled receptacle 10 may then be unscrewed from the threaded socket 29 and replaced by a new unit to be filled. The 20 procedure is then repeated with this new unit.

The function of the coil spring tube 82 in the feed line is to make the resisting torque negligible so that operation of the balance beam 62 will not be restricted. This coil 82 is located 25 near the center of rotation of the beam 62. As shown in Fig. 2, the coil 82 is located substantially below the ball-bearing mounted axle 63.

The pump 90, while described as a hand pump, 30 may be replaced by a power pump or, in the alternative, it may be eliminated and the supply tank 94 may be heated to increase the pressure of its contents and thereby to force the flow of fluid through the conduit to the unit being filled. If desired, an accumulator (not shown) may be incorporated in the fluid line 35 between the pump and the coil 82 so that a more uniform flow will result and thereby reduce the variable errors introduced by the pulsations of flow while the balanced beam 62 is moving from its latched position to its unlatched position, as described. The filter 85 functions to prevent the entry of dirt into the filtering head or the receptacle 10. Suitable check valves 101 are provided in the conduits from 40 the pump 90 to the filling unit, for example, between the conduits 88 and 87. It is to be understood, too, that the pump 90 itself contains 45 built-in check valves (not shown).

The valves V of Freon containing tanks 94 50 normally have a comparatively small opening, so that to obtain any substantial flow the pump 90 must exert considerable suction. Normally, a volatile fluid under such suction tends to vaporize and to "vapor lock" the pump. However, it has been found that while the pump 90 will fill with gas for a few strokes of lever 99, the cooling effect of the vaporization of the Freon tends to reduce the vapor pressure of the liquid and to offset the lower suction pressure. The insecticide is normally mixed with Freon in the supply tank 94. This, however, is for convenience only. It could, if desired, be injected separately. Control valves V₁, V₂, of conventional type, may be provided in the conduits 92 and 88.

While a specific embodiment of the invention has been described, it is to be understood that variations in structural detail within the scope of the claims is possible and is contemplated. There is no intention, therefore, of limitation to the exact details shown and described.

What is claimed is:

1. In a device of the character described, a balance beam rotatable about a fulcrum, means for mounting a receptacle to be filled on said beam to one side of said fulcrum, counterbalancing means for said beam, one way valve means in said mounting means and said receptacle also having one way valve means, latch-controlled means to move said valve means into open condition and to maintain said open condition during filling of said receptacle, means for delivering filling fluid from a source into said receptacle through said valve means, and means responsive to the position of said beam for releasing said latch-controlled means when said receptacle has been filled with a prescribed weight of filling fluid.

2. In a device of the character described, a balance beam rotatable about a fulcrum, means for mounting a receptacle to be filled on said beam to one side of said fulcrum, counterbalancing means for said beam, one way valve means in said mounting means and said receptacle also having one way valve means, latch-controlled means to move said valve means into open condition and to maintain said open condition during filling of said receptacle, means for delivering filling fluid from a source into said receptacle through said valve means, means responsive to the position of said beam for releasing said latch-controlled means when said receptacle has been filled with a prescribed weight of filling fluid, and means to restore said valve means to closed condition.

3. In a device of the character described, a balance beam, means for mounting a receptacle to be filled on said beam, valve means in said means, a pump for forcing filling liquid from a source into said receptacle to be filled through said valve means, a coiled conduit connecting said pump and said valve means to eliminate substantially all torque resisting free motion of said balance beam, counterbalancing means for said beam, and means responsive to the position of said balance beam to effect closure of said valve means when said receptacle has been filled with a prescribed weight of the filling fluid.

4. In a device of the character described, a balance beam rotatable about a fulcrum, means for mounting a receptacle to be filled on said beam to one side of said fulcrum, counterbalancing means for said beam, one way valve means in said mounting means and said receptacle having a similar valve, a lever pivotally carried by said beam, a latch member pivotally carried by said lever and engageable with a part of said beam, a fixed stop in the path of travel of another part of said latch member, means engageable with a portion of said lever for moving said valve means to open condition in one position of said lever, said latch means then engaging said part of said beam and maintaining said position of said lever and the open condition of said valve means during filling of said receptacle, and means for delivering filling fluid from a source into said receptacle through said valve means, said fixed stop serving to release said latch member when said receptacle has been filled with a prescribed weight of fluid and has moved said balance beam about said ful-

crum a determined distance in opposition to said counterbalancing means.

5. In a device of the character described, a balance beam rotatable about a fulcrum, means for mounting a receptacle to be filled on said beam to one side of said fulcrum, counterbalancing means for said beam, one way valve means in said mounting means and said receptacle having a similar valve, a lever pivotally carried by said beam, a latch member pivotally carried by said lever and engageable with a part of said beam, a fixed stop in the path of travel of another part of said latch member, means engageable with a portion of said lever for moving said valve means to open condition in one position of said lever, said latch means then engaging said part of said beam and maintaining said position of said lever and the open condition of said valve means during filling of said receptacle, a pump for delivering filling fluid from a source into said receptacle through said valve means, and conduit means connecting said pump and the valve means in said mounting means and which means is free from reaction resisting free motion of said balance beam on its fulcrum, said fixed stop serving to release said latch member when said receptacle has been filled with a prescribed weight of fluid and has moved said balance beam about said fulcrum a determined distance in opposition to said counterbalancing means.

6. In a device of the character described, a balance beam, means for mounting a receptacle to be filled on said beam, valve means in said means, means for forcing filling fluid from a source into said receptacle to be filled through said valve means, filtering means for said fluid, counterbalancing means for said beam, and means responsive to the position of said balance beam to effect closure of said valve means when said receptacle has been filled with a prescribed weight of the filling fluid.

7. In a device of the character described, the subcombination including, a guide shell for receiving a receptacle to be filled and having a nipple containing a valve, a hollow member carried by said shell and having a threaded opening to receive said nipple, a tubular member movable longitudinally of said hollow member, one way valve means in said tubular member, spring means biasing said valve means normally to a closed position, spring means biasing said tubular member normally outwardly of said hollow member, means limiting the biasing action of said last-named spring means, and a hollow rod extending outwardly of said hollow member and engageable with the valve within said nipple to open the latter and said first-named one way valve means when said tubular member is moved in opposition to said second-named spring biasing means.

8. In a device of the character described, the combination including, a guide shell for receiving a receptacle to be filled and having a nipple containing a valve, a hollow member carried by said shell and having a threaded opening to receive said nipple, a tubular member movable longitudinally of said hollow member, one way valve means in said tubular member, spring means biasing said valve means normally to a closed position, spring means biasing said tubular member normally outwardly of said hollow member, means limiting the biasing action of said last-named spring means, a hollow rod extending outwardly of said hollow member and engageable

with the valve contained by said nipple to open the latter and said first-named one way valve means when said tubular member is moved in opposition to said second-named spring biasing means, means for so moving said tubular member, latch means for retaining said tubular member in such moved position, means for forcing filling fluid from a source through said valve means and said receptacle, and means responsive to the weight of said receptacle increasing to a predetermined weight for releasing said latch means.

9. In a device of the character described, means for mounting a receptacle to be filled, a balance beam supporting said means, valve means within said mounting means, latch-operated means for opening said valve means, means including a pump for transferring filling fluid from a source to said receptacle to be filled, and means responsive to the position of said balance lever for releasing said latch-operated means to permit closing of said valve means when said receptacle has been filled with a prescribed weight of the filling fluid.

10. In a device of the character described, means for mounting a receptacle to be filled, a balance beam supporting said means, a counter-weight carried by said beam, valve means within said mounting means, latch-operated means for opening said valve means, means including a pump for transferring filling fluid from a source to said receptacle to be filled, and means responsive to the position of said balance lever for releasing said latch-operated means to permit closing of said valve means when said receptacle has been filled with a prescribed weight of the filling fluid and has overbalanced said counterweight.

11. Apparatus for filling a fluid receptacle having a dispensing outlet projecting therefrom and providing a passage in which there is an inwardly facing valve seat and a valve biased outwardly thereagainst for opening by a removable operator pushed thereagainst through said passage with the latter having a gasket for sealing around this operator, said apparatus including a downwardly movable vertical outer tubular member having in its top an upwardly pointing recess adapted for receiving and releasably engaging

said outlet to thereby support said receptacle, a vertical inner tubular member vertically reciprocatively arranged in said outer member with a spring urging the former downwardly relative the latter and a retainer for preventing the former from separating from said outer member while permitting thus limited relative downward motion, a downwardly facing feeder valve seat in the upper portion of said inner tubular member and a feeder valve biased upwardly thereagainst, a tubular rod extending from said feeder valve up through said feeder valve seat in a fluid tight reciprocative manner and up into said recess with at least its upper portion sized and shaped to pass through said receptacle's valve operator gasket in a fluid tight manner when said receptacle's valve operator is removed and said rod being adapted to communicate with the relatively opposite sides of both said valve seats when both said valves are forced therefrom, said inner tubular member being adapted to be fed with fluid beneath its said valve seat, a snap acting retainer for holding said inner tubular member upwardly when said outer tubular member is at an up position and which is movable with said outer member, means engaging and releasing said retainer when the latter moves with said outer member and means for biasing said outer tubular member at said up position with a predetermined force.

WAINWRIGHT TUTTLE.
